The ornamental design for the below-headlap portion of a tile, as shown and described.

DESCRIPTION

FIG. 1 is a front elevational view of the below-headlap portion of the tile of our new design;

FIG. 2 is a top view of the below-headlap portion of the tile of FIG. 1;

FIG. 3 is a bottom view of the below-headlap portion of the tile of FIG. 1;

FIG. 4 is a right side view of the below-headlap portion of the tile of FIG. 1;

FIG. 5 is a left side view of the below-headlap portion of the tile of FIG. 1;

FIG. 6 is a fragmentary transverse sectional view taken along the line VI—VI of FIG. 1;

FIG. 7 is a rear view of the unindented rear portion of a below-headlap portion of a tile of FIG. 1; and,

FIG. 8 is a front plan view of a below-headlap portion of a modified form of our new design, and wherein FIGS. 2-7 represent minor images of the top, bottom, right side, left side, fragmentary and rear views thereof, respectively.

The phantom lines illustrate the headlap portion and indented rear of the tile which do not form part of the design, but which are environmental structure.
